SCRAPER SHARPENER

Filed Nov. 10, 1947

UNITED STATES PATENT OFFICE

2,482,419

SCRAPER SHARPENER

George Walter Jerrells, Seattle, Wash.

Application November 10, 1947, Serial No. 784,965

2 Claims. (Cl. 76—88)

1

This invention relates to means designed for the sharpening of scrapers of that type comprising a metal blade that is formed with a straight scraping edge sharpened at a square angle, that is, sharpened straight across the blade body at a ninety-degree angle to the planes of the sides of the blade; such scrapers being used extensively in meat markets for cleaning the top surface of the chopping block.

It is the principal object of this invention to provide a novel means whereby the operation of sharpening the blade edge will be greatly expedited.

It is also an object of the invention to provide a scraper sharpener comprising means for holding a flat file, and including paired guides between which the scraper blade may be moved reciprocally in contact with the file surface to sharpen the blade edge and which guides will hold the blade in a plane perpendicular to the file while so actuated, thus to insure the sharpening of the blade edge at the desired square, ninety-degree angle.

It is also an object of the invention to provide a sharpener of the above stated kind wherein the file may be laterally shifted relative to the guides so that practically all of its surface may be utilized for sharpening.

Yet another object of the invention is to provide the sharpener with a base member having a stop or abutment at one end that may be engaged against the edge of the table or block on which the device is placed for use, to aid in holding the device against endwise movement during a blade sharpening operation and to eliminate the requirement for clamps or other securing means for this purpose.

Still further objects of the invention reside in the details of construction and combination of parts, and in the mode of use of the device, as will hereinafter be fully described.

In accomplishing these and other objects of the invention, I have provided the improved details of construction, the preferred forms of which are illustrated in the accompanying drawings, wherein—

Fig. 1 is a perspective view of a scraper sharpener embodied by the present invention, and illustrating also the mode of applying a scraper thereto for a sharpening operation.

Fig. 2 is a vertical cross-section of the sharpener.

Fig. 3 is a top view of the file holder and scraper guide members comprised in the device.

Fig. 4 is a top view of the base member of the

sharpener, with the scraper guides removed therefrom for a better showing of the file containing recess that is formed in the top surface of the base member.

Fig. 5 is a side view of the sharpener showing the abutment or stop flange at one end of the base member as engaged against the edge of the sharpener support.

Fig. 6 is a front end view of the device.

Referring more in detail to the drawings—

In its present preferred form of construction, the scraper sharpener comprises a rather elongated, rigid base member 10 that is adapted to lie flatly upon a supporting surface such as a table top, or top surface of a meat chopping block. Preferably, this base member is cast of aluminum, or other suitable metal, but may also be hard wood, or plastic and still quite satisfactorily serve its purpose. As observed in Fig. 2, the base member 10 is of an inverted channel form and comprises the opposite side flanges 10a—10a and a flat surfaced top wall 10x. In a practical size for its intended use, it is approximately ten inches long, two inches wide and one inch deep, but these dimensions are in no way critical.

At its forward end, the base 10 is formed with a depending flange 12 designed as a stop or abutment that may be engaged flatly against the side edge of a table top, block or other support, to aid in the proper holding of the device during use. In Fig. 5, this stop 12 is shown as engaged against the edge of a support, designated at 13, upon which the base is disposed for use.

Formed lengthwise of the base, within the top surface of the top wall 10x, and to its full length, is a shallow recess 15 in which a flat file 16 of a common, well known type may be located as shown in Figs. 1, 2 and 4. At one end, this recess opens as shown in Figs. 1 and 4 to the end of the base; the recess being of a width that permits the file to be inserted and withdrawn from the recess endwise. At its other end, the recess has a restricted central opening 18 through which the prong 16x of the file only may be extended; the shoulders at the end of the file, adjacent opposite sides of the prong portion 16x, will engage against the shouldered end surface 19 of the recess as opposite sides of opening 18 to hold the file against endwise shifting in the direction of this end of the recess. It is shown also in Fig. 4, that the recess 15 is of such width that the file may be moved laterally to limited extent for a purpose presently apparent.

Fixed upon the base 10, lengthwise thereof, are

two guide members 20—20 of angle bar form. These guides have horizontal base flanges 20a secured by screws 21 flatly upon the top surface of the base member, as will be understood by reference to Fig. 2. They also have vertical flanges 20b that are disposed in a slightly spaced and parallel relationship to provide a guide slot 24 between them of a width designed to receive the blade portion of a scraper between them for sharpening as has been illustrated in Figs. 1 and 2, wherein the scraper is designated in its entirety by numeral 25 and its blade is designated by numeral 25x.

The guide members 20—20 are secured sufficiently close together to retain the blade in a perpendicular position relative to the top surface of the file as disposed in channel 15 but not to bind the blade to any extent. To accommodate blades of different thickness, the horizontal flange of one of the guide members has somewhat elongated, transversely directed slots, as at 26 in Fig. 3, to receive the screws. When the screws as applied through the slots are loosened, the guide may be adjusted to provide a slot of more or less width. Tightening of the screws then secures the guide at the adjusted position.

With the device so constructed, it is used by placing the base member 10 flatly upon a supporting surface, such as a table top, with the flange 12 engaged against the table edge. Then a file 18 is inserted in the recess as shown in Figs. 1 and 4. The blade of the scraper to be sharpened is then applied to the slot 24, as shown in Fig. 1, and the scraper is reciprocally actuated with the lower edge of its blade flatly in contact with the file. Pressure as required is placed on the blade to obtain the desired sharpening effect. The file may be shifted from side to side in the slot so as to take advantage of a greater part of its surface, and it may be reversed in position to obtain use of both sides.

In order that the file may be held at a set position of lateral adjustment in the recess, I have provided a clamp plate 30 that is set in a transverse recess 31 in the channel 15 near its open end as shown in Fig. 4. The file overlies this plate and the plate may be lifted to clamp the file against the under side of the flanges 20a by means of a set screw 33 that is threaded up through the bottom wall as has been shown in Fig. 6.

Sharpeners of this kind will accurately hold the blade at the proper sharpening angle to get an even square cut edge that is required for satisfactory use of scrapers of this kind. No clamp is required to hold the device in place,

and due to the longitudinal flanges along opposite side edges of the base 10, that engage with the supporting surface, there is no tendency for the device to rock laterally on the support.

Changes in size, proportion and materials may be made without departing from the spirit of the invention.

Having thus described my invention, what I claim as new therein, and desire to secure by Letters Patent is:

1. A scraper sharpener comprising a horizontal base member designed to rest flatly upon a table top for its functional support and having a depending flange at one end for engaging against the table edge; said base member having a recess formed to its full length centrally of its top surface, a file blade disposed flatly therein, said recess being of slightly greater depth than the file thickness and of greater width than the file to permit lateral shifting of the file therein, and open to its full width at one end for the insertion or removal of the file, and having a restricted opening centrally at its other end for passage of the file tang with looseness and providing abutments at opposite sides of the opening against which that end of the file will engage, and a pair of guide bars fixed in parallel, spaced relationship on the base member, lengthwise of the recess, providing an intermediate slot, open at its ends, and adapted to receive the blade of a scraper therein for a sharpening operation; said guide bars being of angle iron form and each having a horizontal flange fixed to the base member, and a vertical flange, said vertical flanges defining the slot and serving to hold the scraper perpendicular and reciprocally movable in contact with the file blade.

2. A device as recited in claim 1 including also a clamp plate disposed in the recess near its open end to underlie the file and a clamping screw threaded upwardly in the base member to engage said clamp plate to effect the clamping of the file between said plate and said guide bars.
